UNITED STATES PATENT OFFICE.

JOHN PENROSE AND ERNST A. PLOEGER, OF CHICAGO, ILLINOIS.

AUTOMATIC RELIEF-VALVE.

1,290,335.

Specification of Letters Patent.

Patented Jan. 7, 1919.

Application filed March 8, 1915. Serial No. 13,028.

To all whom it may concern:

Be it known that we, JOHN PENROSE and ERNST A. PLOEGER, citizens of the United States, residing at Chicago, in the county of 5 Cook and State of Illinois, have jointly invented certain new and useful Improvements in Automatic Relief-Valves, of which the following is a description.

Our invention belongs to that general 10 class of devices known as traps or water relief valves employed on various steam or other systems, and particularly vacuum steam heating systems, to discharge the water of condensation or other fluid from the 15 system without any unnecessary waste or loss of steam. The invention has among its objects the production of a device of the kind described that is extremely simple, efficient, durable, and satisfactory, which is 20 entirely automatic in operation, which will not be affected or rendered inoperative by sediment or accumulation of dirt, and one in which the water of condensation or other fluid will not back up through the system. 25 Other objects and advantages of the construction will be apparent to those skilled in the art, from the disclosure herein given.

To this end our invention consists in the novel construction, arrangement and combination of parts herein shown and described, and more particularly pointed out in the claims.

In the drawings, wherein like reference characters indicate like or corresponding 35 parts,

Figure 1 is a sectional view through the valve;

Fig. 2 is a sectional view taken substantially on line 1, 1 of Fig. 1;

Fig. 3 is a sectional view taken substantially on line 2, 2 of Fig. 1, and

Fig. 4 is a sectional view taken on line 3, 3 of Fig. 1.

Referring to the drawings, our preferred 45 form of valve consists of a casing 1 of suitable shape and material provided with a top or cover 2, which may be removed for convenience in constructing or removing the valve and parts thereof. We have not considered it necessary to illustrate the radiator or vacuum apparatus. The casing is provided with an inlet 3 at one side, which may be formed in the extension 4, and with an outlet 5 extending through the extension 6, 50 the extensions being suitably arranged for attachment in the heating system. The casing

is formed with a depression or pocket below the lower level of the intake, as for example, below the level of point 8, and arranged within the casing, preferably at substantially the level of the lower side of the inlet, is a plate or cross partition 7. This is supported or secured in place in any desired manner, and divides the casing into two chambers, the lower of which may be 60 termed the condensing chamber and the other the vacuum chamber. The partition 7 is formed with an opening or passageway 9 therethrough. While the opening may be placed at any desired point in the 65 plate or partition, it is preferred to place it on the side opposite the inlet or intake, as shown.

Extending between the partition and the outlet 5 is a tubular part 10, the same being 70 so secured in place that all water, air, or other fluid, passing or escaping through the outlet must first pass up through the opening 9 in the partition before passing by the controlling valve and out through the outlet. The part 10 is inwardly extended and 75 formed with a valve seat at the upper end. In the construction shown this is formed in a removable part 11, so that the part may be renewed or conveniently reground from 80 time to time, as found necessary. We also 85 preferably form a valve seat 12 on the under side of the transverse part of part 10, the purpose of which will be more fully explained hereafter. Arranged to coöperate 90 with the valve seat in part 11 is a tubular valve member 15, which is carried by the tubular member or stem 16, provided with a float 17. Any type of float may be employed, that shown being found very satisfactory for the purpose. The tubular stem 95 16 and part 10 in themselves also substantially serve as condensing chambers, should there be any steam or vapor entering the same.

The valve and float are guided and limited 100 in their travel by a member 18, extending through a suitably sized opening or leakage port 14 in the end of the float within the confines of the tubular part 16, springs 19 and 105 20 being arranged between the end of the member 18 and float, between the float and cover 2. The member 18, as shown, is threaded into the cover 2, so that it may be adjusted from the exterior. A pin 23, or its 110 equivalent, is provided to limit the adjustment of the member. It is provided with an

end 21 arranged to be engaged by a suitable key or wrench, the same being normally closed by a cap 22, or its equivalent. The cap 22 prevents any leakage of steam or water from the casing that may pass between the threads of member 18 and the cover.

Arranged in the space of the tubular part 10 below the main valve 15, and arranged to 10 coöperate with the valve seat 12, is an auxiliary or check valve 24. This is normally open and carried by a rack 25, or its equivalent, arranged with guides 26. The member 24 is intended to seat on the valve seat 12, to 15 prevent any back flow of water should for any reason there be a back flow.

Assuming that the valve is closed, as indicated in the drawing, and that there is water in the condensing chamber, or below 20 the partition 7: owing to the suction of the vacuum apparatus, any air that might be in the casing is drawn through the opening 14 past the guide 18, and down through the tubular member 16 past valve 24, and 25 through the outlet 5. If there is any air in the system it is drawn through the inlet 3, and through the water, and up through the opening 9, and thence through opening 14 past guide 18, and out through the outlet 5. 30 Any steam drawn through the inlet is condensed in the water in the condensing chamber. The vacuum apparatus draws the water up through opening 9, but the same, owing to its weight, is not drawn up over 35 the top of the float. As soon, however, as the condensation is enough and sufficient water has been drawn into the vacuum chamber of the casing, or above partition 7, to raise the float, the valve 15 is raised with the float, 40 and the excess water flows past the valve and out through the outlet 5. As soon as the valve seats, however, the flow is cut off. Ordinarily all the steam drawn through the condensing water is condensed, but any 45 steam entering the vacuum chamber and passing out through the tubular valve would be insignificant in quantity, and only vapor, as the opening about guide 18 is small, and it would be condensed in the tubular valve stem and in part 10. The stem or guide 18 always keeps the outlet 14 or leakage port open. The valve may be positively opened at any time, or its adjustment made by turning the guide 18, the pin 23 limiting the adjustment, so that the valve is accurately seated. The device is entirely automatic and noiseless in operation, and practically cannot get out of order. All the steam is condensed at the valve, so that practically all 50 available heat units are extracted substantially at the radiator. Should the valve seat 55 wear or become corroded, it may be easily replaced or the corrosion removed by re-grinding.

60 Having thus described our invention, it is

obvious that various immaterial modifications may be made in the same without departing from the spirit of our invention; hence we do not wish to be understood as limiting ourselves to the exact form, construction, arrangement or combination of parts herein shown and described, or uses mentioned.

What we claim as new and desire to secure by Letters Patent is:—

1. In a device of the kind described and in combination, a suitable casing provided with a transverse partition having an opening therethrough, and with an inlet at one side substantially in alinement with said partition, and an outlet below the partition, a tubular part arranged between said partition and said outlet, connecting the space above the partition with the outlet, said part provided with a valve seat at the upper end 75 thereof, and with a valve seat on the lower face of a portion thereof, valves arranged to coöperate with said valve seats, the valve member arranged above said partition being provided with a tubular extension having a 80 float carried thereby, said extending member having an opening through the top communicating with the interior of the tubular extension, and means depending from the top of the casing for guiding said valve 85 members, comprising an adjustable guiding rod depending from the top of the casing with its outer end extending to the exterior of the casing, and resilient means on said rod for yieldingly limiting the movement 90 of the upper valve relative thereto.

2. In a device of the kind described and in combination, a suitable casing, provided with an inlet at one side, and formed with a pocket below said inlet, an outlet arranged 105 below said inlet, a tubular part extending from said outlet upwardly in the casing, a partition arranged adjacent the end of said tubular part, and substantially at the normal water level within the casing, said partition provided with an opening therethrough, said tubular part inwardly shoudered and formed with a valve seat at each 110 end of said shoulder, a tubular valve arranged to coöperate with the upper valve 115 seat adjacent the end of said tubular part, a tubular stem for said valve member having its upper ends open and in communication with the upper part of the casing chamber, a float carried by said tubular valve stem, 120 and a valve arranged to coöperate with the under valve seat.

3. In a device of the kind described and in combination, a suitable casing provided with an inlet at one side, and formed with a 125 pocket below said inlet, an outlet arranged below said inlet, a tubular part extending from said outlet upwardly in the casing, a partition arranged adjacent the end of said tubular part substantially at the normal 130

water level within the casing, said partition provided with an opening therethrough, said tubular part inwardly shouldered thereabout and formed with a valve seat at each end of said shoulder, a tubular valve arranged to coöperate with the valve seat adjacent the end of said tubular part, a tubular stem for said valve member having its upper end open and in communication with the upper 10 part of the casing chamber, and a float carried by said tubular valve stem, guiding means for said valve member, a valve arranged in said tubular part below said shoulder, and means for supporting said valve in 15 a normally open position.

4. In a device of the kind described, a casing having an inlet in its side elevated above the bottom and an outlet in the bottom of the casing, a partition extending transversely across the casing substantially on the plane of the inlet and having formed therein a central opening provided with a valve seat, and a second opening connecting the two chambers, and a tube connecting the 20 25 30 valved opening in the partition with the outlet and preventing the escape of liquid except through said opening, in combination with a float in the upper chamber mounted on a vertically movable tube provided with a valve on its lower end coöperating with the valve seat in the partition and having an air vent formed near the upper end of the tube, resilient guiding means for the upper end of the tube arranged to cushion the movement of the tube in either direction, and external 50 55 means for regulating the cushioning means, substantially as described.

ranged to cushion the movement of the tube in either direction.

5. In a device of the kind described, a casing having an inlet in its side elevated above the bottom and an outlet in the bottom of the casing, a partition extending transversely across the casing substantially in the 40 plane of the inlet and having formed therein a central opening provided with a valve seat and a second opening connecting the two chambers, and a tube connecting the valved opening in the partition with the outlet, preventing the escape of liquid except through said opening, in combination with a float in the upper chamber mounted on a vertically movable tube provided with a valve on its lower end coöperating with the 45 valve seat in the partition and having an air vent formed near the upper end of the tube, resilient guiding means for the upper end of the tube arranged to cushion the movement of the tube in either direction, and external 50 55 means for regulating the cushioning means, substantially as described.

In testimony whereof, we have hereunto signed our names in the presence of two subscribing witnesses.
